UNITED STATES PATENT OFFICE.

FRANK D. SMITH, OF SPRINGFIELD, MASSACHUSETTS.

CUTTER-HEAD FOR MILLING-MACHINES.

No. 856,306.

Specification of Letters Patent.

Patented June 11, 1907.

Application filed July 27, 1908. Serial No. 328,041.

To all whom it may concern:

Be it known that I, FRANK D. SMITH, a citizen of the United States of America, residing at Springfield, in the county of Hampden and 5 State of Massachusetts, have invented new and useful Improvements in Cutter-Heads for Milling-Machines, of which the following is a specification.

This invention relates to machine tools and 10 has especial reference to the construction of a cutter-head for milling machines, the object of the invention being to provide an improved cutter-head of this class having two spindles supported on a suitable head and rotatable about a common axis independently 15 to permit the cutter of each to work at a different angle from the other, if desired, each spindle being independently rotatable on its own axis and having a common driving connection with the machine; the head on which 20 said spindles are secured also being rotatable in the plane of the axis on which they are rotated for adjustment; a further object of the invention is to provide in the above described construction means to rotate one of 25 said spindles in either direction independently of the other, means being provided to prevent the rotation of this spindle, if desired.

30 The invention is clearly illustrated in the accompanying drawing, in which,—

Figure 1 is a sectional elevation of a cutter-head and its support showing clearly the driving connection for the spindles and the 35 connection of the spindles with the head; also the connection of the latter with a suitable base through which the driving connection from the machine extends. Fig. 2 is a side elevation of the construction shown in 40 Fig. 1. Fig. 3 shows, on a somewhat reduced scale in side elevation, the position of the two spindles in which both are adjusted at the same angle on either side of a vertical line drawn through the axis on which the 45 spindles swing. Fig. 4 is a front elevation showing one of the spindles provided with a cutter and the other provided with a stem and serving as a pilot-spindle for profiling work. Fig. 5 is a side elevation showing both 50 spindles in the same vertical plane one provided with a larger cutter than the other whereby two cuts may be made in a piece of work at different depths and at the same time. Fig. 6 is a side elevation showing both 55 cutters adjusted to the same horizontal plane

whereby two cuts may be made in a piece of work at the same time, as for example, in cutting a rack-gear.

Referring now to these drawings, *a* is a base-piece which may be of any suitable form 60 adapted to be secured to a milling machine or like tool in position to permit a driving-shaft *b* having a suitable driving connection with the machine, to extend through it. This base-piece *a* has formed in one end 65 thereof a circular T-groove *c* into which studs *d* (T-shaped in cross section to correspond with the groove) may enter. These studs are secured to a spindle-head *e* and one end extends through the head and is provided with a nut (not shown) whereby the head may be secured to the base in any adjusted position in the manner well known in 70 this class of machines.

The spindle-head *e* carries a shaft *f* on 75 which is a beveled gear *g* in mesh with a like beveled gear *h* on the driving-shaft *b*, both of these shafts being provided with suitable bearings in the head, and on opposite ends of the shaft *f* are beveled gears *k* and *m*. The 80 ends of the head *e*, through which the shaft *f* and the gears *k* and *m* extend, are squared off at right angles to said shaft and provided with a circular T-groove *o*, spindle-casings *p* and *p'* having studs to enter said grooves *o* 85 being mounted on each end of said head. Each of these spindle-casings carries a hollow spindle (indicated respectively by *q* and *r*), each spindle being vertically adjustable in its casing in the manner to be described further on, and one end of each spindle being provided with any well known tool-holding chuck, as for example, the well known tapered split-jawed chuck *s*, shown in the spindle *q*. 90

In the spindle-casing *p* is a beveled gear *t* in mesh with the gear *k*, and having a spline and groove connection with the spindle *q* whereby the latter may be rotated by, and at the same time be freely movable through, the 100 gear. In the casing *p'* two beveled gears *v* and *w* are located similar in all respects to the gear *t*, except that they have no spline and groove connection with the spindle, and these gears *v* and *w* are located on the spindle *r* in 105 mesh with the gear *m* on the shaft *f* at opposite points thereon, the inner ends of each of the gears *v* and *w* being provided with clutch-teeth *x*. Located between these two gears and on the spindle *r* is a clutch-collar *y* 110

also provided with clutch-teeth to engage those of either of the above mentioned gears, said collar having a spline and groove connection with the spindle. The collar is provided with a forked arm 3 extending through the spindle-casing and pivotally supported therein on a pin 4 whereby said collar may be thrown into clutch with either of the gears, it being clear that when in clutch with one of the latter, the spindle rotates in one direction and when in clutch with the other, in the opposite direction.

From the foregoing description, it is seen that the rotation of the shaft *b* will, through the gears *h* and *g*, rotate the shaft *f* which, in turn, will rotate the spindle *q* always in the same direction; but the spindle *r* may be rotated in either direction according as the clutch-collar *y* is thrown into clutch with the gear *v* or the gear *w*. When the clutch-collar is located equi-distantly between these two gears, the spindle *r* will remain idle.

Means to feed the spindle axially toward and from the work are provided and consist of the following mechanism: The upper end of each spindle has fitted thereto an externally screw-threaded sleeve 5 in which the spindle revolves, and screwed over this sleeve is another one 6 having a flange 7 which rotates in a groove formed by the upper end of the spindle-casing and by a flanged cap 8 screwing down onto it. The upper end of the sleeve 6 is preferably provided with an annular flange 9 for spanner-holes whereby the sleeve 6 may be rotated to move the sleeve 5 vertically. This latter is prevented from turning by means of a key 10 which enters a straight groove 12 extending from top to bottom of the sleeve, and the thrust of the latter downward is taken by a pin 13 extending through the spindle or any other suitable abutment. The thrust upward is taken by a nut 14 screwed onto the end of the spindle provided with a check-nut 15.

In Fig. 1 the left-hand spindle is shown in a raised position and the right-hand spindle is shown in a lowered position, the construction of the feed devices on both spindles being the same. Each of the spindle-casings *p* and *p'* is provided with a removable cap 16 located opposite the ends of the shaft *f*, to the end that access may be had to the interior thereof for purposes of examination for lubrication, and a like cap is secured to the under side of the head *e* to cover the recess therein in which the bevel-gears *h* and *g* are located. On referring to Fig. 3, it is seen that this construction permits of an adjustment of spindles in which the tool-carrying end of either spindle may be swung to the right or left of a vertical line extending through the axis on which the spindles are swung for adjustment, thus making it possible to work on oppositely located undercut walls at the same time.

Fig. 4 shows in what manner the spindles may be used on a profiling job,—one of the spindles being provided with a cutter 17 and the other with a pilot-spindle 18, the work being indicated by 19 and the pattern-plate by 20, both being secured to the work-bed 21 of a milling machine; and as this bed is provided with feed-screws to move it in rectangular directions, these may be operated by the workmen to hold the pattern-plate 20 in contact with the pilot-spindle 18 thus permitting the reproduction of the pattern on the work 19.

Fig. 5 shows still another adjustment of the spindle whereby two parallel cuts of different depths may be made at the same time by alining the spindles vertically and applying thereto cutters of different diameters and feeding the work past both cutters.

Fig. 6 shows each of the spindles swung to a position at right angles to the vertical plane, one on each side of the latter, and provided with cutters of the same diameter whereby the machine may be used for cutting the teeth of rack-gears; or, if desired, still another adjustment may be made (which, however, it was not thought necessary to illustrate in the drawings,) in which one of the spindles will be adjusted to vertical position, as shown in Fig. 4, and the other to a position at right angles to the first,—that is in the position shown in Fig. 6.

It is obvious that the machine is capable of an infinite variety of adjustments other than those described and illustrated in this application, but it is thought that enough has been shown and described to clearly emphasize the utility and novelty of the invention.

Still another useful feature of the machine showing its adaptability to a great variety of work may be illustrated by assuming that a cut is to be made on either side of a piece of work and however narrow the piece may be, the head may be rotated to bring the cutter on each spindle to bear on each side of the piece, the latter being secured to the work-bed of the machine in position to be fed past both cutters.

What I claim is:

1. The combination with a suitable head rotatable in a fixed plane, two spindles on said head rotatably mounted thereon to swing in parallel planes and at right angles to the plane of rotation of the head, a driving-shaft in said head, and suitable driving connections between said shaft and said spindles, and feeding devices associated with the spindles to move them axially.
2. The combination with a head rotatable in a fixed plane, a shaft rotatably mounted in said head, spindle-casings rotatably mounted on opposite ends of the head concentrically with said shaft and capable of adjustment in parallel planes, spindles in said casings, driving-gears for the spindles in

mesh with other gears on said shaft, feeding devices to move the spindles axially, and means to rotate said shaft.

3. The combination with a head rotatable in a fixed plane, a shaft rotatably mounted in said head, spindle-casings rotatably mounted on opposite ends of the head concentrically with said shaft and at right angles thereto, and capable of adjustment in parallel planes, driving-gears in said casings in mesh with other gears on said shaft, spindles in the casings having a rotative engagement with the gears therein and having endwise movement relative to said gears, together with feeding devices for the spindles to move them axially in either direction, and means to rotate said shaft.

4. The combination with a milling machine or like tool, of a suitable head rotatable in a fixed plane, a spindle on each end of said head rotatably mounted thereon to swing in parallel planes and at right angles to the plane of rotation of the head, a driving-shaft in said head, and suitable driving connections between said shaft and said spindles whereby the latter may be rotated in the same, or in opposite directions, independently, and feeding devices associated with each spindle to move the latter axially.

30 5. The combination with a milling machine or like tool, of a suitable head rotatable in a fixed plane, a spindle on each end of said head, rotatably mounted thereon to swing

in parallel planes and at right angles to the plane of rotation of the head, a driving-shaft in said head, and a driving connection for said shaft located on the axis of rotation of the head, gears to rotate the spindles, and other gears on the driving-shaft meshing with those on the spindles, and independent means to feed the spindles axially, together with means to rotate one of said spindles in an opposite direction to the other.

6. The combination with a milling machine or like tool, of a suitable head rotatable in a fixed plane, two spindles on said head rotatably mounted thereon to swing in parallel planes and at right angles to the plane of rotation of the head, a driving-shaft in said head, a beveled gear thereon engaging another beveled gear on one of said spindles to rotate it in one direction, a beveled gear on the opposite end of said shaft, and two beveled gears on the spindle adjacent thereto in mesh with the gear on the driving-shaft, and a clutch-collar on the spindle between said gears having a rotative engagement with the spindle whereby the shifting of the collar into clutch with the gears on the spindle will effect the rotation of the latter in opposite directions, together with independent feeding devices for the spindles.
